HERMAN STRATER, JR., OF BOSTON, MASSACHUSETTS.

Letters Patent No. 98,814, dated January 11, 1870.

IMPROVEMENT IN WATER-CLOSET VALVES.

The Schedule referred to in these Letters Patent and making part of the same.

To all whom it may concern:

Be it known that I, HERMAN STRATER, Jr., of Boston, in the county of Suffolk and State of Massachusetts, have invented an Improved Water-Closet Valve; and I do hereby declare that the following, taken in connection with the drawings which accompany and form part of this specification, is a description of my invention sufficient to enable those skilled in the art to practice it.

My invention relates to the construction of water-closet valves of that class in which the valve is so arranged as to be prevented from sudden closing, the water continuing to flow past the valve after the pan is raised by the weighted lever, so as to fill the pan sufficiently to flush or seal the bottom of the hopper with water.

My improvement has particular reference to the arrangement of the inlet-pipe and its induction-orifices, and to the arrangement and construction of the slow-closing valve.

The drawings represent a water-closet valve or cock, embodying my invention.

A shows a vertical central section of the valve.

B, an under side view of the cap and the induction-pipe.

C, a side view of the valve.

a denotes the body or main chamber of the cock, containing the valve-seat *b*, upon which rests the bottom of the valve *c*, from the bottom of which valve projects down the vertical spindle *d*, which rests upon the pan-operating lever.

This valve is formed cup-shaped, or has over it a cup or chamber, *e*, from one side of which (near the bottom) leads a fine orifice, *f*, covered by a strainer, *g*.

In this chamber or cylinder is a stationary piston, *h*, at the end of a stem, *i*, projecting down from a diaphragm, *j*, extending across the bottom of the inlet-tube, or from the cap *k*, and the cylinder *e* plays vertically upon this piston.

At the top of the cock is a cap, *k*, which is made as a flanged ring, the ring screwing down upon the top of the body *a*, and its flange *l*, projecting inwardly, over the edge of a round washer-plate, *m*, (which is a continuation of the diaphragm plate *j*) a leather or other suitable packing-ring, *o*, being interposed between the washer-plate *m* and the top edge of the body *a*, to pack the joints between the cap and the body, and between the inlet-pipe and the cap.

The washer-plate turns around freely in the cap-ring, (when the ring is loosened,) thus allowing the inlet-pipe *s* to be set at any angle relatively to the outlet-pipe *x*.

This pipe *x* leads from an auxiliary chamber, *n*, under the valve-seat, as seen at A, and when the valve is raised, water rushes through the valve-seat

opening into such chamber *n*, and out through the pipe *x* into the water-closet hopper, to cleanse the closet.

When the weighted lever that operates the pan is raised, it raises with it the valve-stem *d*, and lifts the valve *c* from its seat.

The inlet-pipe *s* opens directly into the main chamber *a*, and keeps the chamber filled, and, when the valve is opened, water rushes from the main chamber into the auxiliary chamber, and thence into the bowl or hopper of the water-closet.

The cylinder is also filled with water (beneath the plunger) when the valve is closed, and, as the valve rises, the upward movement of the cylinder causes this water to be pressed out through the orifice *f* and the gauze *g*.

When the pan-operating lever is allowed to fall, it drops from the valve-stem, and the valve, instead of immediately closing, only falls down to its seat as fast as water from the main chamber can percolate through the gauze and aperture into the cylinder beneath the plunger, thus keeping the valve open after the pan has risen, and allowing water to flow into and rise in the pan until the valve reaches its seat and shuts off further flow of water from the main into the auxiliary chamber, at which time the water in the pan will have sealed the bottom of the hopper or container.

The valve is moved down by gravity and by the friction and downward pressure of the current of water.

To increase the pressure-surface, I make, upon the outer surface of the valve-cylinder, a series of shoulders or projections, *p*, furnishing surfaces against which the pressure of the water acts to hasten or facilitate the descent of the valve.

When the head of water is not great, a spring, *q*, may also be used, the stress of such spring tending to force the valve down, as will be readily understood.

In slow-closing valves, as heretofore made, the outlet-pipe and inlet-pipe have both led directly from the main body or valve-containing case, and have been relatively fixed upon opposite ends of the said case, whereas it is often desirable to have the inlet and outlet-pipes not in the same plane, but capable of relative angular adjustment.

It is also desirable to have the water enter so as to press or flow equally upon all sides of the valve or plunger-cylinder.

For these reasons, I bring the inlet-pipe into the top of the case or through the centre of the cap, and connect it by a joint that will permit the inlet-pipe to be set at any angle relatively to the outlet-pipe, or *vice versa*.

I claim, in combination with the valve-containing

case, and its valve and suitable inlet and outlet-pipes, the reciprocating cap or cylinder, (over the valve,) and the stationary piston, constructed and arranged to operate substantially as described.

Also, in combination with the reciprocating cylinder *e*, the shoulders *p*, substantially as shown and described.

Also, in combination with the reciprocating valve *c* and cylinder *e*, the spring *q*, substantially as described.

HERMAN STRATER, JR.
